UNITED STATES PATENT OFFICE.

DAVID JAMES ROGERS, OF BARDSTOWN, ASSIGNOR OF ONE-HALF TO
GEORGE T. SANSBURY, OF LEBANON, KENTUCKY.

HEATING-STOVE.

SPECIFICATION forming part of Letters Patent No. 368,116, dated August 9, 1887.

Application filed August 30, 1886. Serial No. 212,236. (No model.)

To all whom it may concern:

Be it known that I, DAVID JAMES ROGERS, of Bardstown, in the county of Nelson and State of Kentucky, have invented a new and 5 useful Improvement in Heating-Stoves, of which the following is a specification.

My invention is an improved base for a vertical heating-stove. It is formed of four principal parts, to wit: a top plate on which the 10 bowl of the stove is supported, a subjacent grate-supporting frame, a sub-base, and a series of uprights or posts which support both 15 said top plate and frame clear from the sub-base. In this space a removable ash-pan forms the sides of the stove-base in place of the usual casting.

The main features of construction and the details of above-named parts will be herein-after described.

20 In the accompanying drawings, Figure 1 is a perspective view of a stove provided with my improved base. Fig. 2 is a central vertical section of the base. Fig. 3 is a perspective view of the base detached, and showing the 25 grate in position therein. Fig. 4 is a side view of the base.

The bowl A of the stove rests in a socket formed in the top plate or base proper, B. This plate rests on a skeleton frame, C, which supports the grate D, and is in turn supported on uprights or posts E, standing on the sub-base F. The latter has the usual detachable feet, a. The frame C is composed of three parts, the outer ring or section, 1, the inner concentric ring, 2, and the connecting-arms 3, all of 35 which are cast in one piece. The said inner ring, 2, is made of less inner or clear diameter than the diameter of grate D, to adapt it to support the latter. Its top edge is beveled 40 outwardly, so that ashes will not find lodgment thereon. To hold the grate in place on said support 2, lugs 4, Fig. 2, are cast on the under side of the top plate, B; but the lugs may be made separate, as shown in Fig. 3.

45 Thus, when the grate is pushed in through the opening at the front it comes in contact with the said lugs, as shown, and is thereby caused to assume and retain a due position directly under the opening in the top plate, B, through 50 which ashes and cinders are discharged from

the bowl A of the stove. Thus the lugs not only define the position of the grate, but prevent it from working out of place when being oscillated, but do not of course hinder withdrawal of the grate through the slot or opening at the front of frame C. The outer section, 1, of frame C is separated from the top plate, B, by a narrow space, through which a poker may be inserted for the purpose of "stirring the fire." (See Fig. 4.)

55 The above-described lugs are preferably extended, and made of sufficient thickness to separate these parts sufficiently to allow insertion of a poker, as stated; but, of course, lugs 5, cast on the frame C, as in Fig. 3, might 60 effect the same purpose.

65 There is a narrow space, Fig. 2, between the grate D and the top plate, B, which allows insertion of the poker between them, and also facilitates discharge of ashes when the grate is 70 oscillated, which is effected by inserting the poker or other suitable implement in the socket in the handle b of grate. (See Fig. 1.)

75 For a coal-stove, the grate is provided with elongated openings. I shall, however, make it solid or without openings when applied to a stove designed for burning wood.

80 The uprights or posts E, that support the top plate, B, and frame C on the sub-base F, are made hollow to receive bolts G, that pass also through the top plate, B, frame C, and sub-base F, and are provided with nuts c, to adapt them to clamp said parts securely together.

85 The ash-pan H is made of sheet or other thin metal, and of such circumference and height that it will occupy the clear space between the posts E and the sub-base F and frame C. When the said pan H is drawn forward it of course removes the bulk of the ashes. Such as remain scattered on the sub-base F may be conveniently swept off by a broom, the clear space between the posts allowing convenient insertion and use of the latter for this purpose.

90 At the top of the stove I show a damper, I, which regulates the draft through the space between the top plate and frame and the grate. The trunnions of the damper rest in notches formed in the ring c, and are held therein by the section of the stove-pipe which said ring 95

enters. In some cases the base of the stove will be made square, and of course the base B and frame C will then have a like form.

What I claim is—

- 5 1. In a base for a heating-stove, the combination of the grate-supporting frame C with the top or socket plate, B, which rests thereon, but is separated therefrom by narrow spaces or slots, as shown and described.
- 10 2. In a base for a heating-stove, the combination of the grate-supporting frame C, the top plate, B, and the lugs which are interposed between said parts, as shown and described.
- 15 3. In a base for a vertical heating-stove, the combination, with a grate-supporting frame and the top plate, B, and sub-base F, of a series of uprights or columns which rest on the latter and support said frame and top plate, thus leaving a clear space that facilitates removal of ashes or cinders, as specified.
- 20 4. In a base for a vertical heating-stove, the combination, with the sub-base, the top plate, and the interposed frame, of a series of up-

rights or columns supporting said top plate and frame, and bolts for securing the parts together, as shown and described. 25

5. In a base for a vertical heating-stove, the combination, with the stove-base formed of the top plate, a grate-supporting frame, the sub-base, and a series of uprights which support said top plate and frame clear from the sub-base, of an ash-pan adapted to occupy the space between the sub-base frame and posts, as specified. 30

6. In a base for a vertical heating-stove, the combination, with the top plate, grate-supporting frame, posts, and sub-base F, of a removable ash-pan which forms the sides of such stove-base and thus takes the place of the casting or fixed part ordinarily employed, for the 35 purpose specified. 40
